UNITED STATES PATENT OFFICE

98,656

DESIGN FOR LEATHER OR SIMILAR ARTICLE

Morris White, New York, N. Y.

Application December 17, 1935, Serial No. 60,136

Term of patent 7 years

To all whom it may concern:

Be it known that I, Morris White, a citizen of the United States, residing at New York, in the county of New York and the State of New York, have invented a new, original, and ornamental Design for Leather or Similar Article, of which the following is a specification, reference being had to the accompanying drawing, forming part thereof.

Fig. 1 is a plan view showing my new design.

Fig. 2 is an edge view.

My new design consists essentially in the provision in the surface of the leather, or other

similar material of spaced parallel lines of closely arranged minute indentations and spaced arcuate lines of similar indentations extending between said parallel lines of indentations, such lines of indentations simulating stitching. As illustrated in the drawing, the design is applied to a sheet of leather or similar material of suitable dimensions for use in the manufacture of a pouch for ladies' handbags, or the like.

I claim:

The ornamental design for leather or similar article, substantially as shown and described.

MORRIS WHITE.
